UNITED STATES PATENT OFFICE.

CARL MUEHLEISEN, OF BERLIN, GERMANY, ASSIGNOR TO MERGENTHALER LINOTYPE COMPANY, OF BROOKLYN, NEW YORK.

TYPOGRAPHICAL COMPOSING MACHINE.

Application filed January 24, 1923. Serial No. 614,549.

To all whom it may concern:

Be it known that I, CARL MUEHLEISEN, a citizen of the United States of America, and residing at Sellerstrasse 13, Berlin, N. 39, 5 Germany, have invented new and useful Improvements in Typographical Composing Machines, of which the following is a specification.

It is already known for a typographical 10 composing machine to be provided with a column of superposed magazines, movable up and down by screws or cams, to bring any of said magazines into operative position. In order to facilitate the movement 15 of the column, it has heretofore been proposed to employ springs for counterbalancing the weight of the magazine column.

The above type of machine, as hitherto constructed, has admitted of the use of only 20 a limited number of magazines; if the number of magazines were increased beyond that limit the weight of the column would be excessive, and moreover, if, say eight or more magazines were used, a considerable 25 amount of force would be exerted laterally, rearwardly or frontwise resulting in considerable friction, so that notwithstanding the provision of counterbalancing springs or reducing gears, the raising and lowering of the magazines would still present appreciable difficulty.

According to the present invention, all the force emanating from the magazine column and directed laterally, frontwise or rearwardly, will be removed or neutralized, 35 owing to the fact that said magazine column is supported substantially about its centre of gravity or in a vertical plane passing through or containing the centre of gravity, so that the column of magazines as a whole, 40 will exert upon its support a force directed only downwards and substantially vertically, and that the employment of reducing gear will make it possible for the column 45 to be easily raised or lowered without any appreciable friction resistance opposing said movement.

The drawings illustrate by way of example one constructional form of the present 50 invention and in these:—

Figure 1 is a side elevation of a machine according to the present invention with the frame partly broken away to reveal parts which would otherwise be obscured;

Figure 2 is a front elevation of Figure 1; 55

Figure 3 is an illustration of the magazine column and its operating mechanism;

Figure 4 is portion of a plan shown partly in section, of certain of the devices shown in Figure 3; 60

Figure 5 is a part elevation as seen from the right of Figure 3;

Figure 6 illustrates the machine frame and an oscillating magazine supporting frame; 65

Figure 7 is a plan of the oscillating frame shown in Figure 6 and partly broken away;

Figure 8 illustrates a further constructional form of the magazine suspension means, and

Figure 9 is an elevation as seen from the left of Figure 8, and partly in section. 70

The column of magazines in each of the constructional forms exemplified, comprises eight superposed magazines 1.

Each of the said magazines is provided, 75 in the known manner, with a magazine frame 2. All the eight magazine frames are connected together as a single rigid entity, by means of three bars or rails 3, 4 and 5, at each side of the column, these bars, as indicated more particularly in Figures 3 and 8, being connected with the several magazine frames 2 by screws or bolts. The several bars 3, 4 and 5 are secured to a base plate 6 so that the whole magazine column, apart 80 from the capacity of interchangeability of the individual magazines, forms a rigid entity. To give additional strength, diagonal bars 7 may be provided, these, also, being secured to the magazine frames 2 by screws 85 or bolts. 90

In or somewhere near the vertical plane containing the centre of gravity of the magazine column, is a horizontal rod 8 (Figures 3 and 5) mounted in the base plate 6 and 95 pivotally connecting the latter with an approximately triangular frame or link 9. The latter, in its turn, carries a rod 10 upon which are pivotally mounted two rollers 11 adapted to travel along two rails 12, rigidly connected to the machine frame 13, and inclined parallelly with the path of the magazine column. On the rod 10 is pivoted the upper end of a link 14 whose lower end is pivoted to a lever arm 15, fast on a shaft 16 pivotally supported in bearings in the machine frame 13, and upon this shaft 16 is rigidly secured a bent arm 17 to whose 100 105

free end is pivoted a sprocket wheel 44, see particularly Figures 1 and 2. Under this sprocket wheel 44 and over a second sprocket wheel 19 turning loosely upon the shaft 16, 5 passes a chain 18, one extremity of which is anchored to a hook 45 fast to the machine frame 13. The chain 18 hangs loosely from the hook 45, and thereafter is passed beneath a guide roller 18^a, over the sprocket wheel 19 and thence under the sprocket wheel 44 to a pair of double hooks 20. With these hooks 20 are engaged the lower ends of four springs 21 whose upper extremities are attached to a second pair of double hooks 22 10 connected to the upper part of the machine frame. The springs 21, through the medium of the chain 18, tend to turn the sprocket wheel 19 clockwise on the shaft 16. The sprocket wheel 19 is rigidly connected 15 to the boss or hollow shaft of a worm wheel 23 and this worm wheel is in engagement with a tangent screw or worm 24 which is rotatably mounted in an extension of the lever arm 17, which, like the lever 15, is keyed to the shaft 16. In view of this connection, the attachment of the sprocket wheel 19 to the lever arm 15 is rigid excepting as regards the capacity for relative angular adjustment by rotating the worm 24, 20 and as the weight of the magazine column is opposed to the influence of the springs 21, these latter cannot, without extraneous aid, turn the sprocket wheel 19. The chain is therefore securely held by the sprocket 25 wheel 19, and the springs 21, through their action upon the sprocket wheel 44, tend to turn the shaft 16 and lever arms 15 and 17 30 as a single entity, anti-clockwise.

By turning the worm 24, the sprocket 40 wheel 19 can be moved angularly about the shaft 16, so that the chain 18 will be correspondingly tightened or loosened and the tension of the springs 21 adjusted. The springs 21, which, as previously mentioned, 45 turn the arm 17 anti-clockwise, and therefore correspondingly move the arm 15 through the shaft 16, consequently act in opposition to the weight of the magazine column. The lever arm 17 is so connected 50 with the shaft 16 that when the springs 21 are extended, the effective length of said arm is shortened, and when the column of magazines reaches its highest point, i. e. when the springs are somewhat slack, this lever arm 55 is of greater effective length so as almost to neutralize the effect of the difference in the tension of the springs, and thereby oppose to the column of magazines an approximately uniform counterpoise in all positions 60 of the latter.

The column of magazines is mounted in a special frame constructed substantially as shown in Figure 6. The said frame, for a purpose hereinafter mentioned, is pivotally 65 mounted near its uppermost corner, upon a

bar or trunnion 25 fast to the machine frame 13. It carries on either side two toothed racks 26, 27, meshing respectively with two spur wheels 28, 29, rotatably supported by the base plate 6 of the magazine column, as 70 shown best in Figure 3. Upon the shafts of the spur wheels 28, 29, are mounted two helical gears 30 meshing with helical pinions 31 on a shaft 32, which latter is connected to a shaft 34 through a universal 75 joint 33. As the shaft 32 is mounted in brackets on the base plate 6 of the magazine column and moves with the latter, the foremost extremity of the shaft 34, which is fitted with a crank handle 35, is slidably 80 supported in a bearing which is pivoted to the machine frame. By turning this crank handle 35, and through the just described devices, the magazine column can be raised and lowered within the supporting frame 85 which, as before described, is pivoted at 25. For convenience of description this last-named frame is hereinafter referred to as the oscillating frame and is identified as a whole by the reference numeral 90. In 90 order to guide the column of magazines within the oscillating frame 90, the before described rails 3, 4, on the former, engage with rollers 36 on the latter as shown in Figures 3, 4 and 7, and moreover, additional 95 guidance is provided for the magazine column, by rollers 89 pivotally mounted on the base plate 6 of the latter at both sides thereof and tracking along the back and front sides of the respective tooth racks 27. It is 100 understood that the rollers 36 as well as the rails 3 and 4 are provided at both sides of the column of magazines. The common axis of the two rollers 36 is located in an inclined plane which also passes through the 105 distributor entrances and the assembler entrance, and contains the pivot 25 of the oscillating frame, so as to ensure that the magazine which, for the time being, is in 110 operative position will be held in its proper relationship to the assembler and distributor.

The magazine column is provided with further guides constituted by guide rollers 37 and 38 (Figures 2 and 4) mounted on the machine frame. The rollers 37 are 115 adapted to bear against the outer sides of the before described rails 4, to prevent lateral displacement of the upper ends of the magazines relatively to the magazine entrances, whilst the rollers 38 by similarly 120 acting on the bars 5 prevent the lateral displacement of the lower ends of the magazines relatively to the assembler entrance.

In order to lock the column of magazines in an elevated position, a peripherally 125 notched disc 39 is rigidly secured on the shaft 32, while on the base plate 6 of the magazine column, is mounted a two armed lever 40 free to rock about its pivot 41 and connected by a rod 42 with a hand lever 43 130

pivots mounted on the machine frame. One of the arms of the lever 40 is adapted to engage with the notch of the disc 39 and thereby prevent the rotation of the shaft 32. 5 When, for the purpose of adjusting the magazines, it is desired to turn the shaft 32, the hand lever 43 is rocked forward so as to disengage the arm 40 from the notch of the disc 39, and thereafter the crank 10 handle 35 may be turned for securing an operative change of magazine.

It is preferred that the gearing between the crank handle 35 and the racks 26, 27 be so designed or proportioned that a given 15 number of complete revolutions must be imparted to the crank handle 35 to effect a change of magazine, so that the notch of the disc 39 will always be left in position for receiving the locking lever 40 at the 20 completion of such number of revolutions; in such a construction only a single notch is required in the disc 39. If, however, the construction be such as to render it necessary, for making an effective change of 25 magazine, to turn the crank handle 35 through part only of a revolution or through anything short of a complete number of such revolutions, then the number of locking notches in the disc 39 must be correspondingly varied.

The reason for pivotally supporting the oscillating frame on the trunnion 25 is to enable either of any two adjacent magazines to be brought into operative position by 35 rocking the whole column of magazines about the trunnion 25 after the magazines have been raised or lowered to bring the said two magazines to the required level. For this same purpose, the machine is fitted 40 with two distributors 46, 47, each in known manner equipped with distributor screws, and both arranged to work simultaneously. Each distributor co-operates with a separate magazine entrance connecting it with 45 the respective magazine. The magazine entrances as shown in Figure 1 are divided each into an upper portion 48 or 49 and a lower portion 50 or 51. The mutually registering surfaces of these portions are of 50 arcural form, the arcs having for their centre the axis of the trunnion 25. Further the portions 50 and 51 are somewhat wider than are the portions 48, 49 so that when the column is rocked and said portions 50, 51 55 occupy their extreme positions, they will yet coincide with the upper portions 48, 49. By the columnwise adjustment of the magazines, two adjacent magazines are brought into operative relationship with the magazine 60 entrance parts 50, 51, and consequently also with the two distributors 46, 47, so that the matrices can simultaneously be distributed into both of these magazines. By rocking the oscillating frame 90 and with it, the 65 magazine column, the lower end of one of

these same two magazines can be brought into co-operative register with the escapement mechanism controlled from the keyboard 53 and with the assembler entrances 52 (Figures 1 and 2); by these means matrices can be released alternatively from either of the two selected magazines and assembled in the same line. 70

For effecting the rocking of the oscillating frame 90 and magazine column about 75 the trunnion 25, there is provided a crank handle 54 (Figures 1 and 2) fast to a horizontal shaft 55, upon which is also secured a helical pinion 56 meshing with a wheel 57 fast to a shaft 58. Upon the last named 80 shaft there is secured an eccentric or cam 59 bearing against a roller 60 pivotally mounted upon the oscillating frame. In the position shown in Figure 1 the oscillating frame 90, has been rocked towards the 85 left into its foremost position; when the eccentric 59 is turned 180° from the position in which it is shown in Figure 1, the said oscillating frame will be rocked towards the right into its rearmost position. 90 It is understood that the cam shaft 58 may be extended to pass completely under the magazine column and that eccentrics 59 and rollers 60 may be provided on either side of the oscillating frame as shown in Figure 7. 95

Each of the magazines is provided, in known manner, with a matrix escapement mechanism which is not illustrated in the drawings and whose movement is controlled in known manner by vertically movable 100 escapement rods 61 (Figure 1) controlled from the keyboard 53. Each of the escapement rods is guided near its upper end by a wire traversing a slot therein and in a comb-like guide 62. According to the present invention the guide 62 is mounted upon a two armed lever 63 movable about a pivot 64, and of which, one arm is connected through a link 65 with one arm of a three armed lever 67 movable about a stationary 110 pivot 66. The second arm of the lever 67 is connected by a tension spring 68 to a spur or projection on the lever 63 and constantly tends to move the escapement rods towards the magazines and maintains the 115 roller 69 in contact with the cam 70. The third arm of the lever 67 carries a roller 69 which rests upon a cam disc 70, fast to the before described shaft 55. 120

When the crank handle 54 and shaft 55 are turned for rocking the magazines, the cam disc 70 raises the roller 69 and rocks the lever 67 clockwise as viewed in Figure 1, so that, through the link 65, the upper end of the lever 63 will be rocked towards the left, against the influence of the spring 68, and the upper ends of the escapement rods 61 will thereby be moved away from the magazine column and held clear of the magazines during their rocking or swing- 130

ing motion. Near the end of the magazine changing operation, the lever 67 moves anti-clockwise and the link 65 and spring 68 restores the escapement rods 61 to their operative position.

- The swinging of the escapement rods 61 away from the magazine column must take place not only during the time that the oscillating frame 90 is rocked, but also during 10 the time the said column is moved up or down within the said frame. For this purpose the lever 63 is provided at its upper end with a pivoted roller 71, and the oscillating frame is provided with an inclined 15 shaft 72 carrying a block or arm 73. The surface of the block or arm 73 against which the roller 71 bears, although not so shown, is concentric with the axis of the rocking trunnion 25, so that when the oscillating frame is rocked, the position of roller 71 and lever 63 will be unaffected by such motion, that is, assuming that the roller 71 has not been moved away from the arm 73 by the cam disc 70 and associated mechanism 20 previously described. Parallel to the shaft 72 and rigidly connected thereto, is a bail or rail 74 (Figures 1, 2 and 4) along whose rear edge travels a roller 75 rotatably mounted upon an arm of the before described lever 40. When the hand lever 43 is pulled forward for unlocking the magazine changing mechanism prior to actually effecting such change, and the lever 40 is thereby rocked, the roller 75 by pressing 25 against the bail 74 thereby turns the shaft 72, so that the arm 73, by acting upon the roller 71 will rock the lever 63 and through the guide 62 move the escapement rods 61 forwardly into their inoperative position.
- 40 In Figures 8 and 9 is illustrated a further constructional form of the present invention, in which the column of magazines is not supported below its centre of gravity, as in the before described example, but on a line passing through the centre of gravity itself. The column is here supported by trunnions 76 co-axial with the just-named line, the said trunnions being carried by a U-shaped rigid frame formed of vertical 45 bars 77 and a base plate 78. The base plate 78 is supported on bars or legs 79 vertically slidable in guides 80 which are themselves supported with a capacity for rocking, upon footstep bearings 82. Compression springs 81 between the base plate 50 78 and flanges on the guides 80 practically counterbalance the weight of the magazine column. In this constructional form the arrangements for raising and lowering the 55 magazine column and rocking it may be identical with those previously described. In Figure 9 only the uppermost magazine 1 is represented it being assumed that the other magazines have been removed.
- 60 65 It is to be understood that there are other

constructional forms available for supporting the magazine column, for example, they may be supported above the centre of gravity or be fitted with a guide which would be kinematically the equivalent of a support at the centre of gravity. It is also to be understood that the raising, lowering and rocking of the magazines may be effected by mechanism other than that previously described. If more than two distributors are employed, the oscillating frame may be so arranged that it can be rocked into three different positions in order to permit the assembly of matrices from three immediately adjacent magazines. When a single distributor only is employed the frame within which the magazines are movable columnwise, may itself be stationary, that is to say, devoid of the capacity for rocking.

Having described my invention, I declare that what I claim and desire to secure by Letters Patent is:—

1. In a typographical composing machine having a column of superposed magazines adjustable upwardly and downwardly in an inclined path to bring the magazines alternatively into operative position, a support for the column of magazines located approximately in the vertical plane passing through the centre of gravity of the said column.

2. In a typographical composing machine having a column of superposed magazines adjustable upwardly and downwardly in an inclined path to bring the magazines alternatively into operative position, a support for the column of magazines adjustable therewith and arranged to be located approximately in the vertical plane passing through the centre of gravity of the said column in the different adjusted positions of the latter.

3. In a typographical composing machine having a column of superposed magazines adjustable to bring the magazines alternatively into operative position, the combination of a support in operative connection with the magazine column and located approximately in the vertical plane passing through the center of gravity of said column, a rail inclined parallelly with the path of the magazine column over which the said support travels during the adjustment of the magazine column and counter-balancing springs opposing the travel of the support on the inclined rail.

4. In a typographical composing machine having a column of superposed magazines adjustable to bring the magazines alternatively into operative position, the combination of a support in operative connection with the magazine column, a rail inclined parallelly with the path of the magazine column over which the said support travels during the adjustment of the magazine col-

umn, a lever system operatively connected to the support, counterbalancing springs opposing the travel of the support on the inclined rail, a sprocket wheel on an arm 5 of the lever system, and a chain operatively fast to the springs and engaging the sprocket wheel, and adapted to maintain the effective power of the springs practically uniform throughout the longitudinal movement 10 of the chain in either direction.

5. In a typographical composing machine having a column of superposed magazines adjustable to bring the magazines alternatively into operative position, the combination 15 of a support in operative connection with the magazine column, a rail inclined parallelly with the path of the magazine column over which the said support travels during the adjustment of the magazine column, a lever system operatively connected 20 to the support, counterbalancing springs opposing the travel of the support on the inclined rail, a sprocket wheel on an arm of the lever system, a chain operatively fast to the springs and engaging the sprocket wheel, and adapted to maintain the effective power 25 of the springs practically uniform throughout the longitudinal movement of the chain in either direction, a sprocket wheel angularly adjustable on the shaft of the arm and engaged by the chain, and means operative to effect such adjustment of the last-named sprocket wheel and retain it in adjusted position.

35 6. In a typographical composing machine having a column of superposed magazines adjustable to bring the magazines alternatively into operative position, the combination 40 of a support in operative connection with the magazine column, a rail inclined parallelly with the path of the magazine column over which the said support travels during the adjustment of the magazine column, a lever system operatively connected 45 to the support, counterbalancing springs opposing the travel of the support on the inclined rail, a sprocket wheel on an arm of the lever system, a chain operatively fast to the springs and engaging the sprocket wheel, and adapted to maintain the effective power 50 of the springs practically uniform throughout the longitudinal movement of the chain in either direction, a sprocket wheel angularly adjustable on the shaft of the arm and engaged by the chain, a worm wheel fast to the last-named sprocket wheel and a worm engaging said worm wheel rotatable in bearings operatively fast to the arm of the lever system for effecting the said adjustment of the last-named sprocket wheel.

60 7. In a typographical composing machine, the combination of a column of superposed magazines provided with escapement mechanism, distributing mechanism, assembling

mechanism including a set of key-controlled escapement actuating rods, means operative to raise and lower the magazine column to bring a selected plurality of magazines into operative relationship to the distributing mechanism, means operative to move the magazine column to bring any magazine of the selected plurality into operative relationship to the assembling mechanism, and automatic means operative to move the escapement actuating rods into and out of engaging relation to the escapement mechanism of the magazines when the last mentioned means are actuated.

8. In a typographical composing machine, the combination of a column of superposed magazines, a frame pivoted to and capable of being oscillated in the fixed frame of the machine and within which the magazine column is capable of being moved up and down, means operative to rock the oscillating frame on its pivot along with the magazine column within it, locking means to hold the frame in its rocked position, escapement mechanism on the magazines, key-controlled rods for actuating the escapement mechanism, and means actuated by the locking means for moving the escapement actuating rods out of and into engaging relation to the escapement mechanism before and after the actuation of the aforesaid frame rocking means.

9. In a typographical composing machine, the combination of a column of superposed magazines, a frame pivoted to and capable of being oscillated in the fixed frame of the machine, means for raising and lowering the magazine column within the oscillating frame, means for rocking the oscillating frame on its pivot along with the magazine column and its raising and lowering means, escapement mechanism on the magazines, key-controlled rods for actuating the escapement mechanism, and means operated by the actuation of either of the aforesaid means to move the escapement actuating rods into and out of engaging relation to the escapement mechanism.

10. In a typographical composing machine, the combination of a column of superposed magazines, a frame pivoted to and capable of being oscillated in the fixed frame of the machine, a plurality of stationary and simultaneously operative distributors, means operative to raise and lower the magazine column in the oscillating frame to bring into operative relationship with the distributors a corresponding number of the magazines, a single assembler entrance, and means operative to rock the oscillating frame to bring into operative relationship with that entrance one or other of the magazines then registering with the distributors.

11. In a typographical composing ma-

chine, the combination with a column of superposed magazines, of a frame pivoted to and capable of being oscillated in the fixed frame of the machine, and within which the magazine column is capable of being moved bodily up and down, means operative to rock the oscillating frame on its pivot along with the magazine column within it, escapement mechanism on the magazines, key-controlled rods normally operatively engaging said escapement mechanism, and devices operatively connected with the aforesaid rocking means operative to automatically move the rods into and out of engagement with the escapement mechanism when said rocking means are themselves actuated.

12. In a typographical composing machine, the combination with a column of superposed magazines, of a frame pivoted to and capable of being oscillated in the fixed frame of the machine, and within which the magazine column is capable of being moved bodily up and down, means operative to raise and lower the magazine column within the oscillating frame, locking devices for the said means, escapement mechanism on the magazines, key-controlled rods normally in operative engagement with said escapement mechanism, and devices operatively connected with the locking devices operative to move the rods into and out of engagement with the escapement mechanism when said locking devices are themselves actuated.

13. In a typographical composing machine, the combination with a column of superposed magazines, of a frame pivoted to and capable of being oscillated in the fixed frame of the machine, and within which the magazine column is capable of being moved bodily up and down, means operative to rock the oscillating frame on its pivot together with the magazine column within it, means operative to raise and lower the magazine column within the oscillating frame, locking devices for said means, escapement mechanism on the magazines, key-controlled rods normally in operative engagement with said escapement mechanism, a cam operatively connected with the rocking means and devices operatively connected with the locking devices adapted alternatively to move the rods out of engagement with the escapement mechanism, and a spring adapted to return the escapement rods into operative engagement with the escapement mechanism.

14. In a typographical composing machine, the combination with a column of superposed magazines, of a frame pivoted to and capable of being oscillated in the fixed frame of the machine, and within which the magazine column is capable of being moved bodily up and down, means operative to raise and lower the magazine

column within the oscillating frame, locking devices for the said means, escapement mechanism on the magazines, key-controlled rods normally in operative engagement with said escapement mechanism, an upstanding bail pivotally mounted on the oscillating frame operatively contacting with the locking device throughout the whole range of motion of the magazine column within the oscillating frame, a guide for the escapement rods, a lever fast to the guide, and means connecting the bail with the lever and operative to disengage the rods from the escapement devices during the operation of the locking devices.

15. In a typographical composing machine, the combination with a column of superposed magazines, of a frame pivoted to and capable of being oscillated in the fixed frame of the machine, means operative to move said column bodily relatively to the oscillating frame to bring any of the magazines into operative position relatively to the distributing mechanism, guide rails fast to the magazine column, and rollers pivotally mounted on the oscillating frame engaging said rails in the plane passing through the distributor and assembler entrances.

16. In a typographical composing machine, the combination with a column of superposed magazines adjustable to bring the magazines alternatively into operative position, a support for the column of magazines located approximately in the vertical plane passing through the centre of gravity of the said column, of guide rails fast to the magazine column, and guide rollers rotatably mounted on the machine frame and engaging the outer faces of the guide rails to prevent lateral displacement of said column.

17. In a typographical composing machine, the combination with a column of superposed magazines, of a frame pivoted to and capable of being oscillated in the fixed frame of the machine, and within which the magazine column is capable of being moved bodily up and down, a crank handle and means operative to move said column bodily up and down within the oscillating frame to bring any of the magazines into operative position relatively to the distributing mechanism, hand-lever controlled locking devices adapted to secure the said means in adjusted position, and a crank handle and means operative to rock the oscillating frame on its pivot to move a magazine into and out of operative register with the assembling mechanism, the crank handles and hand levers being located closely adjacent each other and closely adjacent the keyboard so as to be readily accessible to the operator seated at said keyboard.

18. In a typographical composing machine, the combination with a column of

- superposed magazines, of a frame pivoted to and capable of being oscillated in the fixed frame of the machine, and within which the magazine column is capable of being moved 5 bodily up and down, a plurality of simultaneously operating distributors, and a corresponding member of magazine entrances formed in two parts one rockable with the oscillating frame, the opposed ends of the 10 said two parts being arcual about a centre co-axial with the pivot of the oscillating frame.
19. In a typographical composing machine, the combination with a column of 15 superposed magazines, of a frame pivoted to and capable of being oscillated in the fixed frame of the machine, and within which the magazine column is capable of being moved bodily up and down, a plurality of simultaneously operating distributors, and a corresponding number of magazine entrances formed in two parts one rockable with the oscillating frame, the opposed ends of the said two parts being arcual about 20 a centre co-axial with the pivot of the oscillating frame, the mouths of the rockable parts being flared so as to be wide enough to maintain access thereinto in all their different positions.
20. In a typographical composing machine, the combination with a magazine column adjustable up and down to bring different magazines alternatively into operative position, springs operative to counterbalance said column, and lever mechanism connecting the springs with said column and adapted to equalize the power exerted by them on the column throughout their varying degrees of elongation and contraction.
21. In a typographical composing machine, the combination with a magazine column adjustable up and down to bring different magazines alternatively into operative position, springs operative to counterbalance said column, a shaft operatively connected to the magazine column so as to be moved angularly in one direction by the weight of said column, and a lever arm operatively engaged with the springs and fast 45 on the shaft in such angular position as to present increased effective leverage with the shortening and weakening of the springs and reduced effective leverage with the lengthening of the springs.
22. In a typographical composing machine, the combination of a column of superposed magazines adjustable upwardly and downwardly to bring the magazines alternatively into operative position, and means 50 for counterbalancing the weight of the magazine column, the said means including a lever system operatively connected to the magazine column, a spring arrangement connected to the lever system and tending constantly to lift the magazine column, a sprocket wheel on an arm of the lever system, and a chain operatively fast to the springs and engaging the sprocket wheel, and adapted to maintain the effective power of the springs practically uniform throughout the longitudinal movement of the chain in either direction.
23. In a typographical composing machine, the combination of a column of superposed magazines adjustable upwardly and 75 downwardly to bring the magazines alternatively into operative position, and means for counterbalancing the weight of the magazine column, the said means including a lever system operatively connected to the magazine column, a spring arrangement connected to the lever system and tending constantly to lift the magazine column, a sprocket wheel on an arm of the lever system, a chain operatively fast to the springs 80 and engaging the sprocket wheel, and adapted to maintain the effective power of the springs practically uniform throughout the longitudinal movement of the chain in either direction, a sprocket wheel angularly adjustable on the shaft of the arm and engaged by the chain, and means operative to effect such adjustment of the last-named sprocket wheel and retain it in adjusted position.
24. In a typographical composing machine, the combination of a column of superposed magazines adjustable upwardly and downwardly to bring the magazines alternatively into operative position, and means 90 for counterbalancing the weight of the magazine column, the said means including a lever system operatively connected to the magazine column, a spring arrangement connected to the lever system and tending constantly to lift the magazine column, a sprocket wheel on an arm of the lever system, a chain operatively fast to the springs 95 and engaging the sprocket wheel, and adapted to maintain the effective power of the springs practically uniform throughout the longitudinal movement of the chain in either direction, a sprocket wheel angularly adjustable on the shaft of the arm and engaged by the chain, and means operative to effect such adjustment of the last-named sprocket wheel and retain it in adjusted position.
25. In a typographical composing machine, the combination of a column of superposed magazines adjustable upwardly and downwardly to bring the magazines alternatively into operative position, and means 100 for counterbalancing the weight of the magazine column, the said means including a lever system operatively connected to the magazine column, a spring arrangement connected to the lever system and tending constantly to lift the magazine column, a sprocket wheel on an arm of the lever system, a chain operatively fast to the springs 105 and engaging the sprocket wheel, and adapted to maintain the effective power of the springs practically uniform throughout the longitudinal movement of the chain in either direction, a sprocket wheel angularly adjustable on the shaft of the arm and engaged by the chain, a worm wheel fast to the last-named sprocket wheel, and a worm 110 engaging said worm wheel rotatable in bearings operatively fast to the arm of the lever system for effecting the said adjustment of the last-named sprocket wheel.
26. In a typographical composing machine, the combination of two distributors, a single assembler entrance, two intermediate magazines movably mounted so that either may be brought into operative relationship to the assembler entrance, and two corresponding magazine entrances for conducting the matrices from the distributors to the magazine in either position of the latter, the said entrances being formed in two parts, one stationary relatively to and 115
- 60 65 70 75 80 85 90 95 100 105 110 115 120 125 130

the other movable with the magazines, and the two being mutually formed to register in either position of the magazines.

26. In a typographical composing machine, the combination of two distributors, two magazines cooperating therewith, a frame pivoted to and capable of being oscillated in the fixed frame of the machine and

within which the magazines are arranged, and two corresponding magazine entrances formed in two parts, one rockable with the oscillating frame, and the opposite ends of the two parts being arcual about a center coaxial with the pivot of the oscillating frame. ¹⁰

CARL MUEHLEISEN.
